(57) **CLAIM**

I claim the ornamental design for a temperature controller for electric mat, as shown and described.

DESCRIPTION

FIG. 1 is a perspective view of a temperature controller for electric mat, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The word “NAVIEN” forming part of the claimed design is a registered trademark of KYUNG DONG NAVIEN CO., LTD.
